UNITED STATES PATENT OFFICE

Application August 11, 1944, Serial No. 549,054
 1-Claim. (Cl. 285—49)

This invention relates to container and nozzle assemblies and to methods of assembling containers and nozzles. More particularly the invention relates to methods of attaching fittings such as nozzles or spouts to metallic container parts, for example can ends, and to assemblies of such fittings and can ends.

An object of the invention is to provide a method of assembling or forming a joint between container parts and fittings such as spouts or nozzles which may be performed quickly and easily and so as to produce a strong serviceable joint.

Another object of the invention is to provide a method of the character referred to which can be performed with a single pressing operation.

Another object of the invention is to provide an assembled container part and nozzle structure having a joint which is very resistant to being opened, damaged, or loosened by blows or the exertion of pressure on the nozzle tending to push the latter towards the container.

Other objects of the invention will become apparent from a reading of the following description, the appended claims, and the accompanying drawing.

In the drawing:

Figure 1 is an axial sectional view of a can end and spout or nozzle assembled in accordance with the invention;

Figure 2 is a fragmentary axial sectional view of the nozzle as it is shaped before being joined to the can end;

Figure 3 is a fragmentary axial sectional view of the can end before it is joined to the nozzle;

Figure 4 is a fragmentary axial sectional view of the nozzle and the can end positioned in readiness for the performance of a pressing operation which is to effect the formation of a joint to complete the assembly;

Figure 5 is an axial sectional view of the can end, the nozzle, and pressing die means, all in positions occupied during an intermediate stage of the pressing operation; and

Figure 6 is a view similar to Figure 5 but showing positions of the parts at the conclusion of the pressing and assembling operation.

The invention is illustrated as applied in the forming of a joint between a spout or nozzle A and a container wall member, for example a metallic can end B. The nozzle A is shown as being conventionally threaded at 1 for receiving a screw cap, but it may instead be formed in any conventional or suitable manner for receiving a different kind of closure such as a stopper

21 to receive a closure of the type shown. The nozzle A is formed of a relatively soft metal, such as aluminum, and an intermediate portion 22 of the nozzle body 3 is formed of a relatively hard metal, such as steel, and is provided with a relatively hard and durable coating, such as tin, to provide a relatively hard and durable coating.

23 (notch) and 24 (notch) are formed in the nozzle body 3 to receive a relatively soft metal, such as aluminum, and an intermediate portion 22 of the nozzle body 3 is formed of a relatively hard metal, such as steel, and is provided with a relatively hard and durable coating, such as tin, to provide a relatively hard and durable coating.

25 (notch) and 26 (notch) are formed in the nozzle body 3 to receive a relatively soft metal, such as aluminum, and an intermediate portion 22 of the nozzle body 3 is formed of a relatively hard metal, such as steel, and is provided with a relatively hard and durable coating, such as tin, to provide a relatively hard and durable coating.

27 (notch) and 28 (notch) are formed in the nozzle body 3 to receive a relatively soft metal, such as aluminum, and an intermediate portion 22 of the nozzle body 3 is formed of a relatively hard metal, such as steel, and is provided with a relatively hard and durable coating, such as tin, to provide a relatively hard and durable coating.

29 (notch) and 30 (notch) are formed in the nozzle body 3 to receive a relatively soft metal, such as aluminum, and an intermediate portion 22 of the nozzle body 3 is formed of a relatively hard metal, such as steel, and is provided with a relatively hard and durable coating, such as tin, to provide a relatively hard and durable coating.

31 (notch) and 32 (notch) are formed in the nozzle body 3 to receive a relatively soft metal, such as aluminum, and an intermediate portion 22 of the nozzle body 3 is formed of a relatively hard metal, such as steel, and is provided with a relatively hard and durable coating, such as tin, to provide a relatively hard and durable coating.

33 (notch) and 34 (notch) are formed in the nozzle body 3 to receive a relatively soft metal, such as aluminum, and an intermediate portion 22 of the nozzle body 3 is formed of a relatively hard metal, such as steel, and is provided with a relatively hard and durable coating, such as tin, to provide a relatively hard and durable coating.

35 (notch) and 36 (notch) are formed in the nozzle body 3 to receive a relatively soft metal, such as aluminum, and an intermediate portion 22 of the nozzle body 3 is formed of a relatively hard metal, such as steel, and is provided with a relatively hard and durable coating, such as tin, to provide a relatively hard and durable coating.

37 (notch) and 38 (notch) are formed in the nozzle body 3 to receive a relatively soft metal, such as aluminum, and an intermediate portion 22 of the nozzle body 3 is formed of a relatively hard metal, such as steel, and is provided with a relatively hard and durable coating, such as tin, to provide a relatively hard and durable coating.

39 (notch) and 40 (notch) are formed in the nozzle body 3 to receive a relatively soft metal, such as aluminum, and an intermediate portion 22 of the nozzle body 3 is formed of a relatively hard metal, such as steel, and is provided with a relatively hard and durable coating, such as tin, to provide a relatively hard and durable coating.

41 (notch) and 42 (notch) are formed in the nozzle body 3 to receive a relatively soft metal, such as aluminum, and an intermediate portion 22 of the nozzle body 3 is formed of a relatively hard metal, such as steel, and is provided with a relatively hard and durable coating, such as tin, to provide a relatively hard and durable coating.

43 (notch) and 44 (notch) are formed in the nozzle body 3 to receive a relatively soft metal, such as aluminum, and an intermediate portion 22 of the nozzle body 3 is formed of a relatively hard metal, such as steel, and is provided with a relatively hard and durable coating, such as tin, to provide a relatively hard and durable coating.

45 (notch) and 46 (notch) are formed in the nozzle body 3 to receive a relatively soft metal, such as aluminum, and an intermediate portion 22 of the nozzle body 3 is formed of a relatively hard metal, such as steel, and is provided with a relatively hard and durable coating, such as tin, to provide a relatively hard and durable coating.

47 (notch) and 48 (notch) are formed in the nozzle body 3 to receive a relatively soft metal, such as aluminum, and an intermediate portion 22 of the nozzle body 3 is formed of a relatively hard metal, such as steel, and is provided with a relatively hard and durable coating, such as tin, to provide a relatively hard and durable coating.

49 (notch) and 50 (notch) are formed in the nozzle body 3 to receive a relatively soft metal, such as aluminum, and an intermediate portion 22 of the nozzle body 3 is formed of a relatively hard metal, such as steel, and is provided with a relatively hard and durable coating, such as tin, to provide a relatively hard and durable coating.

51 (notch) and 52 (notch) are formed in the nozzle body 3 to receive a relatively soft metal, such as aluminum, and an intermediate portion 22 of the nozzle body 3 is formed of a relatively hard metal, such as steel, and is provided with a relatively hard and durable coating, such as tin, to provide a relatively hard and durable coating.

53 (notch) and 54 (notch) are formed in the nozzle body 3 to receive a relatively soft metal, such as aluminum, and an intermediate portion 22 of the nozzle body 3 is formed of a relatively hard metal, such as steel, and is provided with a relatively hard and durable coating, such as tin, to provide a relatively hard and durable coating.

55 (notch) and 56 (notch) are formed in the nozzle body 3 to receive a relatively soft metal, such as aluminum, and an intermediate portion 22 of the nozzle body 3 is formed of a relatively hard metal, such as steel, and is provided with a relatively hard and durable coating, such as tin, to provide a relatively hard and durable coating.

forming portion 6 over the major portion of its area so as finally to compress the intermediate seam forming portion 6, the return bent edge portion 9, and the wall member edge portion 13 all into parallelism with the base portion 12.

Preferably the die 15 is formed with a rib 17 which, during the last phase of the pressing operation, pushes a small ring of the nozzle seam forming portion 4 downwardly to provide a locking bead 18 for preventing lateral shifting or sliding of the parts A and B relative to each other.

It will be observed that this method of assembling the nozzle or spout A and the can end B enables a strong tight joint to be formed with a single pressing operation and without its being necessary to use intermediate dies and to transfer the work to other dies after the parts have been only partially assembled.

In the completed assembly, the spout or nozzle A projects outwardly (upwardly as viewed in Figure 1) from the outside (upper) surface of the can end B. Consequently the nozzle is subject to being struck or pushed, as when cans are packed or piled on one another, tending to push the nozzles from the outside towards the inside of the can end. Because of the novel joint between the nozzle A and can end B such pressure pushing the nozzle A toward the can causes the intermediate portion 6 of the nozzle intermediate seam forming part to push against the underlying joint forming portions 13, 9, and 12, thereby compressing these parts together and tightening the joint rather than opening it.

In the completed assembly the seaming hook 9 of the nozzle interlocks with the seaming hook 13 on the can end. The metal of the nozzle in the region 18 is bent downwardly around the base of the seaming hook 13 and the inclined wall of the can end extends upwardly and bears against the base of the seaming hook 9. This will hold the interlocked hooks in tight engagement which is not in any way disturbed by the springing of the metal parts in the regions adjacent the interlocked hooks. In fact, downward pressure on the nozzle as noted above, tightens the joint rather than loosens the same.

The method and assembly disclosed by way of example are preferred, but it will be apparent that changes could be resorted to without departing

from the invention as defined in the claim.

I claim:

The combination of a container end having a flange at its outer peripheral portion and a central opening, the metal of the end being shaped so as to extend downwardly and inwardly from the flange, thence inwardly and thence upwardly to surround said central opening, the portion of the end surrounding the opening being bent outwardly to form a seaming hook, a nozzle having a vertically disposed body portion provided with a dispensing opening at the upper end thereof, said body portion of the nozzle having at its lower end thereof an outwardly extending portion overlying the seaming hook on the container end and bent back upon itself to form a seaming hook which extends into and interlocks with the seaming hook on the container end, said inclined portion on the end adapted to extend around a portion of the base of the seaming hook on the nozzle and said outwardly extending portion of the nozzle being bent downwardly and tightly around the base of the seaming hook formed on the container end so that downward pressure on the nozzle will tend to draw the inclined portion of the end around the base of the nozzle seaming hook and also draw the outwardly extending portion of the nozzle around the base of the seaming hook on the container end and thereby tighten the same.

JOHN HENCHERT.
